Primary Examiner — Elizabeth J Oswecki(74) *Attorney, Agent, or Firm* — John M. Hammond; Patent Innovations LLC(57) **CLAIM**

The ornamental design for a Christmas tree stand, as shown and described.

DESCRIPTION

FIG. 1 is a top, front perspective view of a Christmas tree stand, showing our new design;

FIG. 2 is a front elevation view thereof;

FIG. 3 is a right side elevation view thereof;

FIG. 4 is a rear elevation view thereof;

FIG. 5 is a left side elevation view thereof;

FIG. 6 is a top plan view thereof;

FIG. 7 is a bottom plan view thereof; and,

FIG. 8 is an exploded, top, front perspective view thereof. The broken lines shown in the drawings represent portions of the Christmas tree stand that form no part of the claimed design.

1 Claim, 6 Drawing Sheets(56)
